UNITED STATES PATENT OFFICE.

FRED M. COURSER, OF HAVERHILL, MASSACHUSETTS, ASSIGNOR TO UNITED SHOE MACHINERY CORPORATION, OF PATERSON, NEW JERSEY, A CORPORATION OF NEW JERSEY.

FOLDING MACHINE.

Application filed April 15, 1921. Serial No. 461,540.

This invention relates to the finishing of the edges of pieces of sheet material and is more particularly concerned with the formation of so-called French edges on pieces of leather.

It is customary in the manufacture of certain styles of boots and shoes to bind the edges of parts of the uppers with a strip of fabric. To this end such a strip is stitched to the edge 5 of the vamp, quarter or other piece, the edge of which is to be bound, cement is applied to the strip, and then the free portion of the strip is folded about the edge of the vamp, quarter or other piece and pressed down so that 10 the cement may hold it firmly in place. The folding of a binding strip, after the strip has been attached to the leather or other piece of material and cemented, may be considered as taking place in two steps. First the free 15 portion of the strip should be pulled out until the stitches "smile," that is, until they can be plainly seen and second, the portion of the fabric which then extends beyond the edge of the leather should be drawn tightly 20 about said edge and laid down upon the margin of the leather.

One feature of the present invention relates to improved means for wiping out the strip of binding. In the illustrative machine this 25 takes the form of a spring-pressed plate set at an angle to the line of feed and adapted, as the work is fed, to wipe out the free portion of the attached binding strip and to cooperate with the folding means in drawing 30 the binding tightly about the edge of the leather or body portion of the work.

Another feature relates to improved folding mechanism which, as herein illustrated, comprises a pair of grippers adapted to 35 seize or grasp the free portion of the fabric and pull it over the edge of the leather. With this construction an extremely effective pull is exerted upon the binding strip with the result that the finished edge is smooth and 40 even.

These and other features of the invention including certain details of construction and combinations of parts will be described as embodied in an illustrated machine and pointed 45 out in the appended claims.

Referring to the accompanying drawings,—

Fig. 1 is a front elevation of a folding machine in which the present invention is em-

bodied, certain parts being shown in section; 55

Fig. 2 is a perspective of a portion of the machine viewed from the rear;

Fig. 3 is a perspective on an enlarged scale 60 of the feeding, folding and pressing members;

Fig. 4 is a perspective showing a piece of work in process of being operated upon;

Fig. 5 is an end elevation of a portion of the machine;

Fig. 6 is a perspective of the same parts 65 shown in Fig. 5;

Fig. 7 is a detail in perspective of part of the presser and feed-foot lifting mechanism, and

Fig. 8 is a perspective of the upper portion 70 of the work supporting post.

Before proceeding to a detailed description of the machine a brief outline of its mode of operation will be given. The machine is designed particularly to fold a binding and 75 will be described particularly in relation to such work although the machine may be used to fold the usual skived edge if desired. In the production of a French edge a strip of fabric, commonly about three-eighths of an 80 inch wide, is laid upon the margin of the grain side of a piece of leather and stitched to the leather by a line of stitches which lies close to the registering edges of the strip and the leather; and then the free portion of the 85 strip or binding is folded around that portion of itself which is attached to the leather, and brought down upon the flesh side of the leather. Prior to the folding operation, cement has been applied to the binding so that 90 when its free portion has been folded as described and brought down upon the flesh side of the leather, it adheres firmly to the leather.

Referring now more particularly to Figs. 95 3 and 4, the work comprises a piece of material 100 such as leather to which a strip of binding 200, such as fabric, has been attached by a line of stitches 300. The arrows in the figures indicate the direction of feed of the work; and in Fig. 4 the leading end of the 100 work has been completely operated upon, that is, the free portion of the binding has been folded about the edge of the leather and pressed down upon the flesh side of the leather while the rear or following end of the work 105 has not yet been operated upon by the machine. In the use of the machine, assuming that the work has been prepared, including

applying cement to the binding strip, the operator pulls out a small portion of the leading end of the binding and turns it upwardly. He then inserts the work in the machine in a manner which will presently be described more in detail with the grain side of the leather resting upon the work support or table 15, the leading end of the binding folded over the leather and located beneath the presser 17, the edge of the work in contact with the edge gage 19, the combined creaser and feed foot 21 and the inner gripper 23 extending into contact or almost into contact with the upturned portion of the binding which has not yet been folded over and pressed down upon the flesh side of the leather and the other or outer gripper 25 spaced from the upturned portion of the binding. Power is then applied to the machine. The presser 17 descends and remains stationary in its lowered position while the two grippers 23, 25 and the feed foot 21 descend. At the same time the outer gripper 25 is swung inwardly until it first presses the upstanding portion of the binding against the inner yielding gripper 23 and then forces the binding inwardly so as to draw it tightly over the outer thin edge of the combined feed foot and creaser 21. About this time the feed foot has descended to force the work against the lower feed member 27. The presser 17 now rises to release the work, and the two feed members 21, 27 together with the grippers are moved forwardly (in the direction of the arrow in the figures) to feed the work one step. At the end of the feed movement, the presser 17 descends again to press the newly folded-over portion of the binding against the flesh side of the leather, and the grippers and feed members return to the positions shown in Fig. 3. The cycle, which has been thus briefly described, is repeated continually, the work being fed and the binding folded progressively by intermittent steps. In order to wipe out that portion of the binding which is on the underside of the leather, a wiper 29 in the form of a thin plate supported upon a spring is set obliquely to the direction of feed of the work. This plate exerts a wiping action upon the under side of the work in a direction outwardly toward the edge of the work and tends to pull the binding outwardly so as to make the stitches "smile". With this brief outline of the mode of operation of the machine, its construction will now be taken up in detail.

The feed mechanism comprises, as has been explained, an upper feed member or foot 21 and a lower feed member 27. Referring now more particularly to Fig. 1 with occasional references to Figs. 5 and 6, the lower feed member 27 is integral with an L-shaped piece which is fastened by screws 31 to and is thus part of a feed yoke 33 which is pivoted to the frame of the machine about a vertical axis coinciding with the axes of the upper and

lower pivot screws 35, 37. Carried by a boss at the upper right-hand corner of the yoke, as viewed in Fig. 1, is a stud 39 which is slidable in a vertical socket formed in an eccentric strap 41 mounted upon an eccentric 45. The eccentric is pivoted upon a disk 46, which is fast to the driving shaft 43, and may be adjusted so as to vary its throw by turning a knurled thumb-hold 47 and thereby causing a pin 49 having a tapered end to move lengthwise of the shaft 43, the tapered end acting upon the stem of a screw 50 carried by the eccentric to move the eccentric substantially transversely of the shaft 43 against the action of a spring 52. This eccentric mechanism for oscillating the feed yoke 33 will not be further described since the details of its construction form no part of the present invention. This mechanism is or may be substantially the same as that shown and described in the patent to Dial et al. No. 718,988. It will be understood, however, that rotation of the shaft 43 through the eccentric mechanism and the pin 39 oscillates the yoke 33 in the desired manner about its pivot screws to cause intermittent feed of the work and that the extent of the intermittent feed movements may be varied by adjusting the eccentric.

The upper feed member or foot 21 has a stem upon the upper end of which is a hub having a bore to receive the lower end of a rod 51, a thumb-screw 53 serving to fasten the hub rigidly to the rod. This rod is vertically slidable in alined bearings 55 formed in the left-hand end (as viewed in Fig. 1) of the upper arm of the yoke 33 so that the rod oscillates with the yoke. In order to cause the rod 51, and with it the upper feed member or foot, to rise and fall at the proper times so as to press upon and release the work, the following mechanism is provided, the same mechanism serving also to cause the raising and lowering of the presser 17.

Referring now more particularly to Figs. 5 and 6, the rod 51 is pivoted at 57 to the lower end of a link 59 the upper end of which is pivoted to the horizontal arm 61 of a bell-crank lever the upright arm 63 of which is in turn pivoted to one end of a link 65. That end of the link 65 remote from the pivotal connection with the upright arm 63 of the bell-crank lever is pivoted at 67 to a crank arm 69 which is rigid with a weighted arm 71 carried by the driving shaft 43. The bell-crank lever is pivoted at 73 to a block 75 fast to the rod 77 at the lower end of which is swiveled the presser 17. The block 75 is acted upon from below by a coiled spring 79, which rests at its bottom upon a part of the overhanging arm 81 of the frame of the machine, and is pressed downwardly by a second coiled spring 83 the upper end of which contacts with a sleeve 85 through which the rod 77 is slidable, said sleeve being threaded through a part of the frame 130

of the machine so as to permit adjustment of the tension of the spring 83. The spring 83 is stronger than the spring 79 and tends at all times to move the rod 77 downwardly until the presser 17 is in contact with the work or the work table.

Assuming that the weighted arm 71 is rotating in the direction indicated by the arrow in Fig. 5, the operation of the mechanism for alternately raising and lowering the presser 17 and upper feed member 21 is as follows: With the parts in the positions shown, the presser 17 is being held down against the work table 15 by the spring 83, and the link 65 is about to be pulled to the right. When this occurs, the bell crank 61, 63 will be rocked in a clockwise direction about the pivot 73 and will thereby force the rod 51, and with it the feed-foot 21 downwardly. This downward movement will continue until the foot 21 contacts with the table 15 or with the work, if work is being fed through the machine. During this time the pivot 73 has acted as a fixed pivot; but as soon as the downward movement of the rod 51 is arrested by contact of the feed foot 21 with the table or with the work, the pivot 57 becomes temporarily fixed, with the result that further clockwise movement of the bell crank 61, 63 lifts the pivot 73, and with it the rod 77 and presser 17. The rod 77 continues to rise as long as the link 65 continues its movement to the right. As soon as the link 65 begins to move to the left and thereby to impart counter-clockwise rotation to the bell crank 61, 63, the rod 77 begins to descend and continues to descend until the presser 17 once more contacts with the table 15 or with the work. At that moment the pivot 73 again becomes temporarily fixed, and the pivot 57 and rod 51 are raised again into the positions shown. Thus it will be seen that first the pivot 73 and then the pivot 57 acts as a fixed pivot, and that the rods 77 and 51 are alternately raised and lowered. The rod 51, as has been explained, is vertically slidable in bearings 55 in one arm of the feed yoke 33; and it will be understood that the movements of the feed yoke are so timed that such movements in connection with the operation of the link mechanism impart to the rod 51 and feed foot 21 a four-motion feed, that is the foot is brought down to clamp the work upon the lower feed member 27, then both the feed foot 21 and member 27 are moved in unison to feed the work forward, then the foot is raised, and finally both the foot and lower feed member are returned to their initial positions ready to grip the work again. The presser 17 holds the work upon the work table during the backward movement of the feed foot 21 and lower feed member 27 and is raised before another forward movement is imparted to the work. The work is thus fed intermittently over the table.

It has been stated above that the free portion of the upturned binding is seized by the grippers, 23, 25 and pulled over the feed foot 21, said feed foot at that time serving somewhat as a creaser, one of its functions being also to hold the leather from being bent upwardly by the pull of the grippers upon the binding. Referring now more particularly to Figs. 2 and 3, the inner gripper 23 (and by "inner" is meant "toward the body of the work") is pivoted about the stem of a screw 87 carried by a sleeve 89 which is fastened to the rod 51 by a set screw 91, said gripper having integral with it a U-shaped arm 93 which extends around the stem of the feed foot 21. A leaf spring 95, the upper end of which is fastened by a screw 97 (Fig. 5) to the hub of the stem of the feed foot bears with its lower end against the U-shaped arm 93 and tends at all times to hold said arm in contact with the stem of the feed foot. The outer gripper 25 is pivoted about the stem of the same screw 87 as is the inner gripper 23 and is swung first in one direction and then in the other at the proper times so as first to co-operate with the inner gripper 23 to pull or fold the binding over the edge of the leather and then to release the binding at the end of an intermittent feed movement, it being understood that the grippers partake of the movements of the feed foot 21 besides having movements of their own. Referring now more particularly to Fig. 1, the outer gripper is connected with the feed yoke 33 by a tension spring 99 which exerts at all times a force tending to rock the gripper away from the inner gripper 23. The limit of this movement is determined by a pin 101 suspended by its head from an eye 103 formed in a stationary part of the machine, the lower end of this pin being provided with a hook which may be inserted in any one of a number of holes formed in the tail of the gripper 25, said tail extending on the other side of the rod 51 from the main portion of the gripper 25. In the figures the gripper 25 is shown in raised position, being held in such position by the action of the spring 99. This position of the gripper is due to the fact that the rod 51 is occupying its uppermost position. When the rod 51 is presently moved downwardly, the sleeve 89, which is fast to the lower end of the rod, is also moved downwardly; and, since the gripper 25 is pivoted to this sleeve and its tail is held from downward movement by the hook at the lower end of the pin 101, the operative, lower portion of the gripper 25 is swung toward the gripper 23 first to grasp the binding and then to pull the binding over the edge of the leather and over the edge of the combined feed foot and creaser 21. When the rod 51 is lifted, the spring 99 returns the gripper 25 to the position shown. With this construction and mounting of the grippers it will be seen that

the locality on the binding strip which is engaged by the grippers depends upon the initial position of the gripper 23 since no gripping occurs until the gripper 25 has been swung far enough to force the binding against the gripper 23. It will also be seen that the initial position of the gripper 23 determines the extent, and hence indirectly the force of the pull of the grippers. The gripper 23 is normally held against the back of the stem of the feed foot 21 by the spring 95 when in its initial position. In order, however, to permit this position to be varied so as to vary the extent of the pull of the grippers and hence the force applied to pull the binding about the edge of the leather, a small rod 24 mounted in a lug on the presser 17 and held in adjusted position by a set screw 26 has an offset projection 28 resembling a crank pin at one end, said projection lying in the path of the gripper 23. Consequently by loosening the set screw 26 and turning the small rod 24 by means of the knurled head 30 the initial position of the gripper 23 may be adjusted.

In order to facilitate manipulation of the work during the folding operation, the work supporting table 15 is carried at the top of an upright post 105 around which is a free and unobstructed space, the lower feed member 27 extending up through the post and through the work supporting surface of the table 15. The edge gage 19 is in the form of a rod bent as shown and held adjustably in position on the post by a set screw 107. The wiper plate 29, one function of which, as has been explained, is to pull out or wipe out the binding so that the grippers may pull it tightly about the edge of the leather, is fast to or integral with a small rod 109, said rod being located in a socket drilled in the post 105 and resting at its lower end upon a small coiled spring 113. This spring is supported by a lug formed on a plate 115 which is vertically adjustable in a slot in the post and is held in adjusted position by a set screw 117. A small pin 119 driven into the post and extending through a slot in the adjusting plate 115 aids in holding said plate in place. With this construction the wiper plate 29 may be adjusted vertically; and after it has been adjusted to its uppermost position, the tension of the spring 113 may be varied.

In order to permit the work to be placed properly in the machine preparatory to the folding operation it is desirable that means be provided for raising the presser 17 and feed foot 21 and holding them in raised position. Referring now more particularly to Fig. 2, treadle controlled mechanism is provided for accomplishing this result. This mechanism comprises a treadle rod 121 so mounted that depression of the treadle (not shown) causes the rod to rise and thereby lift the inner-end of a lever 123 pivoted near its middle portion to a stud 125 carried by the overhang-

ing arm 81 of the machine. The outer end of the lever 123 is pivoted at 127 to the inner end of a bent lever 129 which in turn is pivoted to the overhanging arm 81 at 131. This arm has a substantially horizontal lifter lug 133 extending beneath a small generally L-shaped member 135 which lies beneath the block 75, said block being fast to the rod 77 as has been described. The block 75 is generally L-shaped; and the ends of the block 75 and the L-shaped member 135 are vertically slidable in suitable guideways. The forward guideway is a vertical slot 137; the rear guideway is formed by a boss 139 on the overhanging arm 81 and the inside wall 80 or face of a screw 141. A guide pin 143 driven into the L-shaped member 135 extends up through a bore in the block 75. It will now be clear that when the forward end of the bent lever 129 is rocked upwardly about the pivot 131, the lifter lug 133 will raise the L-shaped member 135 and with it the block 75 and rod 77. Referring now to Fig. 6, it will be seen that raising the block 75 will also result in raising the rod 51 and with it the feed foot 21 and the grippers, since the machine will be at rest and hence the pivot 67 will be for the time fixed. Referring to Fig. 7, it will be seen that the L-shaped member 135 has a downwardly bent ear 235 having a perforation to receive the rod 77, and that the perforated end of this ear extends beneath the spring 79. By this construction the L-shaped member 135 is kept down out of the way of the block 75 during the running of the machine. In order to permit the block 75 and the rods 77 and 51 to be raised at any time and held raised without manipulating the treadle, a cam lifter 145 having a handle 245 is pivoted in the overhanging arm 81 beneath the L-shaped member 135 as best shown in Fig. 2.

It has been explained that the presser 17 is swiveled on the lower end of the rod 77. The purpose of this mounting and of certain mechanism presently to be described, is to facilitate the placing of the work in the machine preparatory to starting the machine. Referring now more particularly to Figs. 2 and 5, the stem of the presser 17 carries an offset hub which is swiveled on the lower end of the rod 77. A coiled tension spring 147 connected at one end to the stem of the presser and at the other to the downwardly bent portion of the lever 129 normally maintains the presser in the angular position shown by holding the upper portion of the rear flat face of its stem against the flat face of an abutment 149. When, however, the treadle of the machine is manipulated to push upwardly the treadle rod 121 and thereby to rock the bent lever 129 about its pivot 131, the lower end of the bent lever is swung to the right, as viewed in Fig. 2, contacts with the stem of the presser 17 at one side of the rod 77 and

swings the presser about its swiveled connection with the rod 77 thereby swinging the presser proper into a position at an angle to the direction of feed of the work. At the 5 same time that this occurs it will be noted that both the rods 51 and 77 are raised so that the feed foot and grippers as well as the presser are raised above the table 15. With the parts thus raised and the presser swung 10 to one side, the right as viewed from the front of the machine as in Fig. 1, the presentation of the work to the machine is greatly facilitated. The operator pulls out and bends upwardly the leading end of the binding and 15 places it in position with the combined feed foot and creaser 21 engaging the edge of the leather, and part of the upturned portion of the binding extending up between the grippers 23, 25. The leading upturned end of 20 the binding at this time is at one side (which would be the left-hand side as viewed in Fig. 1) of the presser which has been swung to the right and is held in that position. The treadle is then released, whereupon the combined feed foot and creaser 21 descends to hold the work against the table 15, lower feed member 27 and wiper plate 29, the latter member yielding through its spring 113. While the feed foot and creaser 21 is descending, 25 the gripper 25 will swing to the left and the upturned portion of the binding which lies in its path will be grasped by the two grippers 25 and 23 and pulled over the edge of the leather and the edge of the combined feed foot and creaser 21. At the same time, 30 that is, during the descent of the feed foot, the presser will swing back (to the left as viewed in Fig. 1) and wipe or push the upturned leading end of the binding over the leather or body portion of the work and in conjunction with this swinging movement will descend. It has been assumed that the feed foot 21 is at the beginning of its forward feed movement, in which case the presser will 35 not descend far enough to press the binding which is beneath it against the leather, but since the leading end of the binding extends only part way beneath the presser in the line of feed, the presser will presently operate 40 upon it.

Assuming then that the work has been presented to the machine, power is applied to the driving shaft 43 through the pulley 151 by manipulating a treadle (not shown) or in 45 any other suitable manner. The operation of the machine is then as follows: The feed foot 21 and lower feed member 27 are swung to the limit of their forward movement, carrying the work, including the fold formed by 50 the grippers, with them. The feed foot and grippers then rise, the grippers releasing the work as they do so, and the presser 17 descends to press the fold. While the presser remains down, the feed foot and grippers, as 55 well as the lower feed member 27, swing to

the limit of their rearward position and presently descend. As soon as the downward movement of the feed foot is arrested by the table 15, the presser rises; and the cycle is then repeated. During the forward movement of the work the wiper 29 drags against the under side of the work and wipes that portion of the binding which is beneath the leather out from beneath it. In performing this operation it not only accomplishes the 70 turning of the free portion of the binding outwardly into a position outside the edge of the leather but also co-operates with the grippers in pulling the binding so as to make the stitches "smile" and thereby in ensuring 75 that the binding shall be pulled tightly about the edge of the leather.

It has been explained above that the operator pulls out a portion of the leading end of the binding strip 200 before he presents the 80 work to the machine. In some cases the operator may roughly pull out the whole strip 200 by hand before presenting the work to the machine. In either case the work may be said to be a sheet of material to one face of 85 which, along an edge of said sheet, an edge of the binding strip is secured so that the strip and the sheet extend at an angle to each other.

Although the invention has been set forth 90 as embodied in a machine for folding French binding, it should be understood that the invention is not limited in the scope of its application to a machine for doing this particular work.

Having thus described my invention, what I claim as new and desire to secure by Letters Patent of the United States is:

1. A folding machine, having in combination, a support for a piece of sheet material, and means for grasping the margin of the sheet material and pulling it over the body portion thereof.

2. A folding machine, having in combination, a support for a piece of sheet material, means for gripping the margin of the sheet material by engagement with both sides of the margin, and means for moving the gripping means in a direction to pull the margin over the body portion of the sheet material.

3. A folding machine, having in combination, a support for a piece of sheet material, means for gripping the margin of the sheet material yieldingly by engagement with both sides of the margin, and means for moving the gripping means in a direction to pull the margin over the body portion of the sheet material.

4. A folding machine, having in combination, a support for a piece of work, means for feeding the work over the support, and means for grasping the margin of the work and pulling it over the body portion thereof.

5. A folding machine, having in combination, a support for a piece of work, means for

- feeding the work intermittently over the support, and means for grasping the margin of the work and pulling it over the body portion thereof.
- 5 6. A folding machine, having in combination, a support for a piece of work, means for feeding the work over the support, means including a pair of grippers for forming a fold in the margin of the work, and means for 10 pressing the fold.
7. A folding machine, having in combination, a support for a piece of work, means for feeding the work over the support, a pair of grippers, means for causing first relative 15 movement of approach of the grippers to grasp the margin of the work and then movement of the grippers in unison to fold the margin of the work over the body portion thereof and means for thereafter pressing the 20 fold.
8. A folding machine having, in combination, a support for the work, means for feeding the work over the support, a creaser for determining the line of fold, a pair of grippers, and means for causing the grippers to 25 engage the margin of the work and pull it over the creaser.
9. A folding machine, having in combination, a support for a piece of work, a feed 30 foot, means for operating the feed foot to feed the work, a pair of grippers movable with the feed foot, and means for moving the grippers transversely of the direction of feed to form the fold.
- 35 10. A folding machine having, in combination, a support for the work, means for feeding the work over the support, a creaser for determining the line of fold, a pair of grippers, means for causing the grippers to engage the margin of the work and pull it over the creaser, and means for pressing the fold.
11. A folding machine, having in combination, a support for a piece of work, a feed 45 foot, means for operating the feed foot to feed the work, a pair of grippers movable with the feed foot, means for moving the grippers transversely of the direction of feed to form the fold, and means for pressing the fold.
- 50 12. A folding machine, having in combination, a support, means including a combined feed foot and creaser for feeding the work and defining the line of fold, a pair of grippers, and means for causing the grippers to 55 seize the margin of the work and pull it over the edge of the combined member.
13. A folding machine, having in combination, a support, a combined feed foot and creaser, means for imparting a four-motion 60 feed movement to the combined member, a pair of grippers, and means for causing the grippers to seize the margin of the work and pull it over the edge of the combined member, the grippers being mounted to move with the 65 combined member.
14. A machine for operating upon a piece of work comprising a piece of sheet material to which a strip is attached having, in combination, a support for the work, a pair of binding-engaging grippers, and means for 70 operating the grippers to pull the free portion of the binding about the edge of the material.
15. A machine for operating upon a piece of work comprising a piece of sheet material 75 to which a strip is attached having, in combination, a support over which the work is fed, a creaser for determining the line of fold, a pair of grippers, and means for causing the grippers to grasp the margin of the 80 work and pull it over the edge of the creaser.
16. A machine for folding a piece of work, comprising a piece of material to which a strip of binding is attached, having in combination, a support for the work, a pair of 85 binding engaging grippers located on the side of the work opposite that to which the strip is attached, and means for operating the grippers to pull the free portion of the binding about the edge of the material.
17. A machine for folding a piece of work comprising a piece of material to which a strip of binding is attached, having, in combination, a support for the work, a pair of 90 binding-engaging grippers located on the side of the work opposite that to which the strip is attached; and means including a spring for operating the grippers to pull the free portion of the binding about the edge of the material.
18. A machine for folding a piece of work comprising a piece of material to which a strip of binding is attached, having, in combination, a support for the work, a creaser 95 the operative edge of which registers substantially with the edge of the material, a pair of binding-engaging grippers, and means for operating the grippers to pull the free portion of the binding over the edge of the material and the edge of the creaser.
19. A machine for folding a piece of work comprising a piece of material to which a strip of binding is attached, having, in combination, a support for the work, a combined feed foot and creaser the operative edge of 100 which registers substantially with the edge of the material, means for operating said member to feed the work, a pair of binding-engaging grippers, and means for operating the grippers to pull the free portion of the binding over the edge of the material and the edge of the combined member.
20. A folding machine, having in combination, a support for the work, means for feeding the work over the support, a pair of grippers for engaging the margin of the work and pulling it, and means whereby the locality on the margin which is engaged by the grippers may be varied.
21. A machine for folding a piece of work 105

comprising a piece of material to which a strip of binding is attached, having, in combination, a support for the work, means for feeding the work, a pair of grippers for engaging the free portion of the binding and pulling it over the edge of the material, and means whereby the locality on the margin which is engaged by the grippers may be varied.

10 22. A machine for folding a piece of work, having in combination, a support for the work, means for feeding the work, a pair of grippers, means for causing the grippers to engage the margin at a predetermined distance from the edge of the material and then to move in unison to pull the margin about the edge of the material, and means for adjusting the initial position of the grippers and thereby increasing or decreasing the 15 force of their pull upon the margin as may be desired.

23. A folding machine, having in combination, feeding and folding members, a fold presser, means for operating the members 25 and presser to feed the work, form the fold and press the fold, and operator controlled means for imparting to the presser sidewise movement with respect to the line of feed to move it out of operative position so as to facilitate 30 presentation of work to the machine.

24. A folding machine, having in combination, feeding and folding members, a fold presser, means for operating the members and presser to feed the work, form the fold 25 and press the fold, and means capable of operation when the machine is at rest for imparting to the presser sidewise movement with respect to the line of feed to move it out of operative position so as to facilitate 40 presentation of work to the machine.

25. A machine for folding a piece of work, comprising a piece of material to which a strip of binding is attached, having in combination, a support for the work, means for feeding the work and for folding the free 45 portion of the fabric over the body material, a fold presser, and means for raising the presser and moving it to one side of the line of feed preparatory to presenting the work 50 to the machine.

26. A machine for folding a piece of work comprising a piece of material to which a strip of binding is attached, having in combination, a support for the work, means for feeding the work and for folding the free portion of the fabric over the body material, a fold presser, and means for raising the presser and moving it to one side of the line of feed preparatory to presenting the work 55 to the machine and for moving it back into operative position after the work has been presented.

27. A machine for folding a piece of work, having in combination, a support for the 60 work, folding means, a feed member and a

fold presser both arranged to engage the upper side of the work, operator controlled means for raising the feed member and fold presser, and mechanism operated thereby for swinging the fold presser to one side of the line of feed.

28. A machine for folding a piece of work, having in combination, a support for the work, folding means, a feed member and a fold presser both arranged to engage the upper side of the work and both located in the path of feed movement of the margin of the work, operator controlled means for raising the feed member and fold presser, mechanism operated thereby for swinging the fold presser to one side of the path of feed movement, and means responsive to the descent of the presser for swinging it back into its first position.

29. A machine for folding a piece of work, having in combination, a support for the work, feeding, folding and fold pressing members located above the work, a binding engaging wiper located beneath the work, the operative face of which lies at an angle 90 to the line of feed, and yielding means for holding the wiper in contact with the work.

30. A machine for folding a piece of work, having in combination, a support for the work, feeding, folding and fold pressing members all located on the side of the work opposite that to which the binding is attached, and a binding engaging wiper located on the same side as that to which the binding is attached, said wiper being mounted for yielding movement away from the work but otherwise held fixed.

31. A machine for folding a piece of work, having in combination, a support for the work, feeding, folding and fold pressing members all located on the side of the work opposite that to which the binding is attached, and a binding engaging wiper located on the same side as that to which the binding is attached, said wiper being in the form 110 of a rib extending at an angle to the line of feed.

32. A folding machine, having in combination, a post of small cross section provided with a work supporting surface on the top thereof there being a free and unobstructed space around said post, a lower feed member extending up through the work supporting surface, an upper feed member, folding and fold-pressing members located above the post, and means for operating all of said members.

33. A machine for folding a piece of work comprising a piece of material to which a strip of binding is attached having, in combination, a support for the work, a pair of grippers, and means for operating the grippers to grasp the free portion of the binding and for moving them in unison to pull the binding over the material.

34. A machine for folding a piece of work

comprising a piece of material to which a strip of binding is attached having, in combination, a support for the work, means for feeding the work intermittently over the support, and means for intermittently grasping the free portion of the binding and pulling it over the material.

35. A folding machine having, in combination, a support for a piece of work, a feed foot, means for moving the feed foot toward and from the work and in a direction to feed the work, a folder carried by the feed foot, and means responsive to movement of the foot toward the work for moving the folder transversely of the direction of feed.

36. The method of folding a strip around the edge of a sheet of material to one face of which, along the said edge, an edge of the strip is secured so that the sheet and the strip extend from the secured-together edges at an angle to each other, the said method comprising first gripping successive portions of the strip, then folding the gripped portions around the secured-together edges, and finally pressing the folded portions into contact with the other face of the sheet.

37. A machine for folding a strip around the edge of a sheet of material to one face of which, along the said edge, an edge of the strip is secured so that the sheet and the strip extend from the secured-together edges at an angle to each other, the said machine having, in combination, means for gripping successive portions of the strip and folding

the gripped portions around the secured-together edges, and means for pressing the folded portions into contact with the other face of the sheet.

38. A machine for folding a strip around the edge of a sheet of material to one face of which, along said edge, an edge of the strip is secured so that the strip and the sheet extend from the secured-together edges at an angle to each other, said machine having, in combination, two gripper jaws adapted to intermittently grip successive portions of the unsecured edge of the strip and pull them across and fold them around the secured-together edges, a fold presser for intermittently pressing the folded portions, and means for actuating the gripper jaws and the fold presser.

39. A machine for operating upon a piece of work consisting of a piece of sheet material to which a strip of binding is attached having, in combination, a support for the work, means for feeding the work over the support, a wiper extending at an angle to the direction of feed movement of the work and adapted to wipe free portions of the binding strip progressively over attached portions thereof as the work is fed, a spring carried by the support and acting to urge the wiper toward the work, and a stop to limit the extent of such movement.

In testimony whereof I have signed my name to this specification.

FRED M. COURSER.
